J. C. SCHWARTZ

TOOTHBRUSH STERILIZER

Filed May 19, 1924

INVENTOR

Jacob C. Schwartz.
By Ralph Reich
ATTORNEY

UNITED STATES PATENT OFFICE.

JACOB C. SCHWARTZ, OF ST. LOUIS, MISSOURI.

TOOTHEBRUSH STERILIZER.

Application filed May 19, 1924. Serial No. 714,360.

To all whom it may concern:

Be it known that I, JACOB C. SCHWARTZ, a citizen of the United States, residing at the city of St. Louis, State of Missouri, have 5 invented a certain new and useful Improvement in Toothbrush Sterilizers, of which the following is a specification, reference being had to the accompanying drawing, forming a part thereof.

10 This invention relates to a certain new and useful improvement in tooth-brush sterilizers.

It is a known fact that many diseases are spread from tooth-brush to tooth-brush, and 15 it is common practice today in many households, so far as I am aware, to suspend the family brushes in group relation upon a rack or the like where they are exposed to contamination not only by one another, but 20 also by the odors, dust, and germs of the bath-room, the breeding, promotion, and spread of diseases frequently resulting.

My present invention has hence for its chief 25 object the provision of means in the form of individual brush-containers equipped with a fume-emitting germicide for effecting separate brush-sterilization.

My invention has also for an object the 30 provision of means of the type and for the purpose stated that is inexpensive in form and convenient not only for suspension or support upon a wall or the like, but also for portability.

My invention has for an additional object 35 the provision of means of the type and for the purpose stated including a fume-emitting germicide in tablet or solid form that may conveniently be renewably disposed within the container and that is effective in 40 the performance of its intended function without injury either to the person or brush.

With the above and other objects in view, 45 my invention resides in the novel features of form, construction, arrangement, and combination of parts hereinafter described and pointed out in the claims.

In the accompanying drawings,—

Figure 1 is an elevational view, partly 50 broken away and in section at its ends, of a tooth-brush sterilizer embodying my invention;

Figure 2 is an elevational view of a plurality of such sterilizers in grouped relation 55 upon a support;

Figure 3 is an end of the group of sterilizers of Figure 2; and

Figure 4 is a perspective view of the sterilizing-tablet proper and its holder.

Referring now more in detail and by reference characters to the drawing, which illustrates a preferred embodiment of my invention, A designates a container, which is preferably in the form of an open-end tubular shell of glass or other suitable material and of suitable dimensions for lengthwise individually housing the usual or standard tooth-brush B.

Fitting removably in the shell A, is a tablet-holding and brush resting member C formed preferably of a single section of suitable sheet metal and integrally comprising a disk 1 having a plurality of perforations or vapor-vents 2 and strips 3 projecting laterally from the disk 1 at diametrically opposite points. The strips 3 are first in suitably spaced relation from the disk 1 bent and flatwise doubled upon themselves in alignment to form or provide a pair of oppositely disposed fingers 4—4, as best seen in Figure 4, and then again bent inwardly at 70 a suitable distance from the fingers 4—4 to form or provide a second pair of oppositely disposed aligning fingers 5, 5, the free ends of the strips 3 being disposed in approximately the axial plane of the disk and bent 75 outwardly or downwardly, as at 6, 6, to project at an angle to the lower set of fingers 5, 5, for yieldingly reinforcing or strengthening the same. Grasped and supported in flatwise spaced relation to and under the disk 1 by the pairs of co-operating fingers 4, 4, and 5, 5, is a disk or tablet 7 of such nature and character as to emit or throw off 80 germicidal fumes or vapors which spread throughout and fill the container or shell A 85 and effect sterilization of the contained brush B. Effectively closing the lower end of shell A, is a preferably threaded imperforate cap 8, and likewise removably closing the upper end of shell A, is a preferably rubber stopper 9 formed preferably with an angular rim or margin, as at 10, to prevent or retard rotary movement of the shell A when 90 loosely placed lengthwise upon a support. Preferably also the stopper 9 is equipped 95 with a depending brush-engaging hook 11 to facilitate conjoint removal of the brush B from its shell or container A on removal of the stopper 9.

I have found my new sterilizer exceedingly efficient in the performance of its intended functions and in the accomplishment of the 100

objects stated. The germicidal matter, being in solid or tablet form, permits of convenient carrying of the shell A in traveling or other handling without its ingredients, frequently disagreeable to the taste and often poisonous to the person, coming in contact with the brush and, in addition, its removal and replacement is most easy and convenient. If desired and as I have illustrated, one or more of the shells A may be supported for ready use upon a wall or the like by means of a suitable rack D.

I am aware that minor changes in the form, construction, arrangement, and combination of the several parts of my new sterilizer may be made and substituted for those herein shown and described without departure from the nature and principle of my invention.

Having thus described my invention, what I claim and desire to secure by Letters Patent is:

1. In a tooth-brush sterilizer, a tablet-holding and brush-resting member comprising a perforated disk and spaced strips projecting laterally from the disk, the strips being first bent and doubled upon themselves intermediate their ends to provide a pair of

oppositely disposed aligning fingers in spaced relation to and under the disk and then again in spaced relation to said first pair of fingers inwardly bent to provide a second pair of oppositely disposed aligning fingers, said pairs of fingers being adapted for co-operation in grasping and flatwise supporting a germicidal tablet under and in spaced relation to the disk. 30 25

2. In a tooth-brush sterilizer, a tablet-holding and brush-resting member formed of a single section of sheet material and integrally comprising a perforated disk and spaced strips projecting laterally from the disk, the strips being first bent and doubled upon themselves intermediate their ends to provide a pair of oppositely disposed aligning fingers in spaced relation to and under the disk and then again in spaced relation to said first pair of fingers inwardly bent to provide a second pair of oppositely disposed aligning fingers, said pairs of fingers being 40 45 adapted for co-operation in grasping and flatwise supporting a germicidal tablet under and in spaced relation to the disk. 50

In testimony whereof, I have signed my name to this specification.

JACOB C. SCHWARTZ.
